Original application July 19, 1935, Serial No.
32,246. Divided and this application Decem-
ber 13, 1935, Serial No. 54,289

10 Claims.

(Cl. 95—34)

arrows, and showing the parts in the position assumed during the paper feeding operation;

Fig. 6 is a transverse sectional view on line 6—6 of Fig. 2 looking in the direction of the arrows, with the parts in the position assumed 5 during the paper feeding operation;

Fig. 7 is a longitudinal vertical sectional view through the control box taken on line 7—7 of Fig. 3, and

Fig. 8 is a detail sectional view on line 8—8 of 10 Fig. 3.

This application is a division of an application filed by us on July 19, 1935, Serial No. 32,246, patented June 2, 1936, Patent No. 2,043,004 to which reference may be had for an understanding of 15 any parts which are not essential to the invention herein claimed and are not fully disclosed herein.

The structure to be described hereinafter is applicable to an electrically or automatically 20 controlled machine, as well as a hand controlled apparatus which is here illustrated, and referring more particularly to the drawings in which like reference characters refer to the same parts throughout the several views, 1 designates a 25 camera body, see Fig. 1, 2 is the usual bellows, 3 is the pivoted magazine normally held in operative relation to the body 1 by the catches 4, and 5 is the roll box or sensitized paper container from which paper is threaded into the magazine 30 3, all substantially in accord with the structures disclosed in Patents Nos. 1,992,492, W. P. Lloyd, February 26, 1935, and 1,998,324, W. P. Lloyd, April 16, 1935.

In the mechanism of Patent No. 1,992,492, the 35 curtain was correlated with the paper feeding mechanism in such a manner that the latter was idle while the curtain was moved to open position, and the paper feed mechanism was operated as the curtain was returned to closed position, thus 40 necessitating returning the curtain after each exposure to feed the paper. In the present structure, the curtain may remain in a fixed open position for successive exposures, and the curtain opening operation serves to control the paper feed mechanism in such a manner that repeated operations of the latter will always effect feeding of 45 a given amount of paper, dependent upon the position of the curtain. The descriptive matter immediately following has to do with the curtain 50 and its operating mechanism.

The curtain is designated at 10, see Figs. 1 and 2, its lower end being fastened to endless chains 11 which travel around sprockets 12 and 13. The upper end of the curtain is fastened to and wound 55 upon a spring roller 14, suitably mounted in the magazine, and which acts to retract the curtain upwardly as the chains to which it is connected are moved in a corresponding direction, and when said chains are moved in the opposite direc- 60

This invention relates to a photo copy machine, with more particular reference to the type of apparatus in which drawings, documents, and the like, are photographed on a sheet of sensitized paper that travels through the machine from a roll, the exposed portion being fed and severed after each exposure, and it has for one object to afford efficient and simple mechanism for controlling the feeding of the paper in order 10 to render more accurate and facilitate the several operations, and to effect an economy in the paper consumption by reducing the amount of wastage.

The principal object of the invention is to afford a simple and practical mechanism in which the amount of paper fed at each paper feeding operation depends upon the position of the curtain and is controlled by a member that is automatically positioned when the curtain is adjusted, and which serves to stop the operation of the paper feeding mechanism in accordance with the position of the curtain so that when the curtain is once positioned at a given point, all subsequent operations of the paper feeding mechanism 25 will cause a fixed amount of paper to be fed, which will not vary until the position of the curtain is again changed.

A further object of the invention is to afford a simple and practical mechanism for effecting the paper feeding operation and including a control member which is operable in one direction to feed the paper and is then adapted to be returned to its initial position.

To these and other ends, the invention consists in the construction and arrangement of parts that will appear from the following description when read in conjunction with the accompanying drawings, the novel features being pointed out in the claims following the specification.

In the drawings:

Fig. 1 is a side elevation partly broken away of a photo copy machine incorporating one embodiment of the invention;

Fig. 2 is a vertical sectional view on the line 2—2 of Fig. 1 looking in the direction of the arrows, and showing the parts arranged for moving the curtain, with the pressure roll in engagement with the feed roll;

Fig. 3 is a horizontal sectional view on line 3—3 of Fig. 2 looking downwardly, the pressure roll being in its elevated position engaged with the feed roll, and the curtain adjusting mechanism in locked position;

Fig. 4 is a transverse vertical sectional view on line 4—4 of Fig. 2 looking in the direction of the arrows, with the parts in neutral position;

Fig. 5 is a transverse vertical sectional view on line 4—4 of Fig. 2 looking in the direction of the

tion, the curtain is drawn by them downwardly to its closed position.

The left hand sprocket 13, see Fig. 2, is splined on an operating shaft 16 so as to turn when the said shaft is rotated, and also permit relative endwise movement of the latter. The shaft 16 has fixed thereon a stop plate 17 with a series of openings 18 therein, see Fig. 7, adapted to selectively engage a fixed stop 19 on the inner surface of the outer wall of the gear box 20, see Fig. 2. The shaft 16 extends through the walls of the gear box and carries an operating handle 21 at its outer end, while 22 is a spring surrounding the shaft 16 and located between the pinion 23 fixed thereon and the inner wall of the gear box, and acting normally to force the operating shaft 16 to its outermost position, as shown in Fig. 3.

To open the curtain, or change the position of the curtain, the handle 21 and shaft 16 are pushed inwardly against the tension of spring 22, as shown in Fig. 2, and the handle 21 is then turned until the curtain is in the desired position for exposure, and upon releasing the handle, the spring 22 forces the shaft outwardly, and one of the openings 18 in stop plate 17 engages the stop 19 and holds the shaft 16, and likewise the curtain, in the position to which it has been adjusted. In the present machine, it is unnecessary to change the position of the curtain after each exposure, or until a different sized opening is desired, and repeated exposures can be made with the curtain in one position. The feed mechanism and the structure by which the curtain setting determines the amount of paper feed will now be described.

The aforementioned pinion 23, see Figs. 2, 3 and 7, on the curtain operating shaft 16 engages and drives a gear 24 which carries on its outer face certain indicia that can be observed through an opening 25 in the gear box 20, see Fig. 1, so that the operator can determine at any time the particular position of the curtain. On the rear face of the gear 24 is a stop or projection 26, see Fig. 3, adapted to cooperate with a stop 27 on a gear 28 that is engaged and driven by a pinion 29, and forms a part of the paper feed mechanism. Pinion 29 is fixed on a shaft 30, see Figs. 2 and 3, which extends through the front wall of the gear box, and carries an operating handle 31 for effecting movement of the paper feed mechanism, the extent of such movement being determined when the aforementioned stop 27 on gear 28 engages stop 26 on gear 24, the position of the latter having previously been determined by the extent to which the curtain is opened. Gear 28 transmits movement to the paper feed roll through the mechanism that will now be described.

Referring to Figs. 1, 2, 3, 4 and 7, the gear 23 is fixed on a shaft 35 which also has fixed thereon and spaced from the gear 28 an operating member or cam 36. Loosely mounted on the shaft 35 is a gear 37 that engages and drives a pinion 38 connected to the paper feed roll. The loosely mounted gear 37 has a projection or stop 49, see Fig. 3, extending from its inner side and engageable with a fixed stop 41 on the gear box to limit the return movement of gear 37 and insure always bringing it back to a definite initial position. 42 is a stop extending from the opposite side of gear 37 into the path of a stop or projection 43 on the adjacent surface of the cam 36, so that when the operating member or cam 36 is turned in an anti-clockwise direction, see Fig. 5, the stop 43 on the cam engages stop

42 on the gear 37 and turns gear 37 correspondingly and likewise the feed roll. The pinion 38, that is actuated by gear 37, is fixed on a shaft which is connected, through a friction roller clutch 44, see Figs. 3 and 8, with the shaft 45 which carries the paper feed roll 46. By arranging the friction clutch 44 between pinion 38 and the paper feed roll 46, the latter is operated when the pinion 38 is driven in one direction, and when the paper feed mechanism is returned to initial position after completion of the feeding operation, the feed roll 46 remains idle to prevent winding the paper backwardly.

The cam 36 is connected to gear 37 in such a way as to effect return of the latter to initial position, and to this end, an arm 48 is loosely mounted on the shaft 35 in the path of the aforementioned stop 42 on gear 37 and is normally held against said stop, as shown in Fig. 4, by a spring 49 connected at one end to the cam 36 and at its opposite end to a lug 50 carried by the arm 48. Thus the spring 49 normally holds the arm 48 against stop 42, and likewise holds stop 40 against stop 41 when the gear is in its initial position, the tension of the spring 49 being sufficient to return the gear 37 to neutral position when the operating member or cam is returned. The spring 49 also permits further reverse movement of the cam 36 to effect operation of paper severing mechanism which forms no part of the invention herein claimed and which it is therefore unnecessary to describe in any further detail.

The paper is fed, after exposure, by turning the handle 31, which actuates feed roll 46, as already described, the latter being then engaged by a pressure roll which holds the paper thereagainst. During the exposure operation, the pressure roll is in a lowered position away from the feed roll and out of the focal plane, the paper being then held by clamping means. Before feeding, the paper is reengaged by the pressure roll, and the clamping means released, and the mechanism which will next be described has to do with the movable pressure roll and clamping means, and the manner in which their operation is controlled.

The pressure roll, designated generally at 51, is mounted on arms 52, see Fig. 6, which are pivoted to swing about an axis 53 whereby the pressure roll is movable from its lower position to its upper position, as shown in Fig. 6, where it is adjacent to the focal plane and holds the paper against the feed roll, and after feeding is completed, when the parts are returned to initial position, the pressure roll is again swung downwardly to its lowered position out of engagement with the feed roll. To accomplish this, each of the arms 52 carries a pivoted sleeve 54, in which is slidably mounted a rod 55 pivotally connected to an arm 56 that is loosely mounted on a rock shaft 57, while 58 is a collar fixed on said rock shaft and carrying an ear 59 arranged to engage a pin 60 on the arm 56. Thus when the rock shaft 57 is turned in a clockwise direction, see Fig. 6, the ear 59 engages pin 60 and swings the arm 56, likewise moving rod 55 upwardly to the position shown in Fig. 6, and swinging the pressure roll into engagement with the paper feed roll preliminarily to the paper feeding operation.

During exposure, the sensitized paper is held against the focal plane plate or back by a clamping means that is automatically removed from engagement with the paper after the pressure roll has engaged the feeding roll, and since this mechanism forms no part of the subject matter of the claims of this application, it is unnecessary

to describe it in any further detail, it being understood that the clamping means is restored to engagement with the paper before disengaging the pressure roll from the feed roll.

- 5 The rock shaft 57 is controlled by the operating member or cam 36 previously described, and to this end, the cam 36 is cut away at 17, see Fig. 5, to receive a roller or projection 78 on the arm 79 which is fixedly mounted on the rock shaft 57.
- 10 These parts are so related that when the operating handle 31 is turned in a clockwise direction and the operating member or cam 36 is at the same time turned in an anti-clockwise direction, the initial part of such movement during the first 45° 15 of turning causes movement of the rock shaft 57 from the neutral position shown in Fig. 4 to the position shown in Fig. 5. During this movement of the cam, the pressure roll is moved upwardly into engagement with the feed roll to the position 20 shown in Fig. 6, and the parts are then ready to feed the paper. Further turning of the cam 36 causes the stop 43 on the cam to engage stop 42 on gear 37 and turn the feed roll, effecting feeding 25 of the paper as already described.
- 25 This feeding movement of the paper continues until the stop 27 on gear 28 engages stop 26 on gear 24, the position of which definitely determines the extent of operation of the feeding mechanism as the parts can move no further.
- 30 The handle 31 which controls the paper feeding mechanism is then turned in a reverse direction to bring the parts previously described back to normal position, and they are then ready for either a paper severing operation or a repetition 35 of the paper feeding operation already described. It will be understood that the rock shaft 57 is returned to its neutral position, when the cam 36 reaches a position to permit such movement, by any suitable spring controlled or other devices 40 connected to rock shaft 57, such for instance as illustrated in the parent application from which this application is a division.

While the invention has been shown and described as applied to certain structural embodiments of a hand-operated machine, it is not necessarily limited in this fashion, and the improvements are equally applicable to an automatic machine or to other embodiments differing in details of construction, and this application is 50 intended to cover any modifications or departures coming within the contemplated purposes of the invention or the scope of the following claims.

We claim:

1. In a photo copy machine, the combination 55 with curtain operating means, of paper feeding mechanism, and stop means automatically adjusted by the curtain operating means and cooperating with the paper feeding mechanism to limit its movement in accordance with the position 60 of the curtain, said stop means being stationary during the paper feeding operation.
2. In a photo copy machine, the combination 65 with curtain operating means, of paper feeding mechanism, and stop means adjustable automatically in accordance with the position of the curtain and cooperating with the paper feeding mechanism to limit its movement after a predetermined amount of paper is fed, said stop means being stationary during the paper feeding 70 operation.
3. In a photo copy machine, the combination

with curtain operating means, of paper feeding mechanism, and a stop carrier driven by the curtain operating means and cooperating with the paper feeding mechanism to limit movement of the latter automatically in accordance with the 5 position of the curtain, said stop carrier being stationary during the paper feeding operation.

4. In a photo copy machine, the combination 10 with curtain operating means, of paper feeding mechanism, a rotatable stop carrier driven by the curtain operating means and adapted to occupy various positions in accordance with the positions of the curtain, the paper feeding mechanism including a second stop carrier, and a stop carried 15 by the latter and engageable with the first mentioned adjustable stop to limit movement of the paper feeding mechanism.

5. In a photo copy machine, the combination 20 with curtain operating means, of paper feeding mechanism, adjustable stop means governed by the curtain operating means and operating when once positioned to limit one or more paper feeding operations in accordance with the position of the curtain.

6. In a photo copy machine, the combination 25 with curtain operating means, of paper feeding mechanism, operable independently of the curtain operating means, and stop means under the control of the curtain operating means acting to limit movement of the paper feeding mechanism 30 in accordance with the position of the curtain.

7. In a photo copy machine, the combination 35 with curtain operating means, of paper feeding mechanism operable independently of the curtain operating means, and stop means automatically adjustable in accordance with the position of the curtain and acting to limit the movement of the paper feeding mechanism.

8. In a photo copy machine, the combination 40 with paper feeding mechanism including a carrier that turns in one direction while feeding paper and in the reverse direction to normal position after feeding, a stop on said carrier, of curtain operating means, and a second stop adjustable automatically in accordance with the position of the curtain and acting to engage the first mentioned stop and thereby limit movement of the paper feeding mechanism.

9. In a photo copy machine, the combination 50 with paper feeding mechanism including a carrier that turns in one direction while feeding paper and in the reverse direction to normal position after feeding, a stop on said carrier, of curtain operating means, a second carrier actuated by the curtain operating means, and a stop on said second carrier cooperating with the first mentioned stop to limit movement of the paper feeding mechanism.

10. In a photo copy machine, the combination 60 with paper feeding mechanism, of curtain operating means, a rotary carrier actuated by the curtain operating means, the paper feeding mechanism including a rotary carrier, said carriers being located in coaxial parallel arrangement, 65 and stops on the carriers cooperating with each other for limiting movement of the paper feeding mechanism in accordance with the position of the curtain.

WHITTEN P. LLOYD. 70
